UNITED STATES PATENT OFFICE.

KOBY KOHN, OF NEW YORK, N. Y., ASSIGNOR TO OSCAR SCHWARZKOPF, OF NEW YORK, N. Y.

REPEATING CAP PISTOL.

Application filed November 14, 1934. Serial No. 749,903.

To all whom it may concern:

Be it known that I, KOBY KOHN, a citizen of the United States, residing at New York, county of New York, State of New York, have invented certain new and useful Improvements in Repeating Cap Pistols, of which the following is a specification.

This invention relates to toy pistols, and more particularly to toy pistols of the repeating type adapted to successively fire a plurality of caps formed on a coiled tape.

It is a general object of this invention to provide a novel and improved form of repeating cap pistol which is unique in construction, certain in operation, simple to manufacture, and comprises the fewest number of parts consistent with satisfactory performance.

More particularly it is an object of this invention to provide a repeating cap pistol which is simplified by combining the cap magazine and hammer in a single unit.

Another object of this invention consists in the provision of a repeating cap pistol in which the cap tape is wholly carried by the magazine-hammer and remains stationary with respect to the casing of the pistol during the cap feeding operation.

Still another object of the invention consists in providing a repeating cap pistol in which the cap tape is carried wholly by the magazine-hammer and moves therewith unobstructedly during the firing stroke of the hammer.

A further object of this invention consists in the provision of means for positively positioning a cap between the anvil and the striking face of the hammer, with every operation of a trigger, irrespective of the initial positioning of the tape or of any inequalities in the spacing, diameter or thickness of the individual caps.

A still further object of the invention consists in the provision of novel means for supporting the magazine-hammer construction for reciprocation within the main casing so that, during the firing operation, it is entirely free to move toward the anvil carrying with it the cap tape with a cap positioned on the hammer face, unobstructed by any tape feeding or positioning parts or any other parts which would tend to resist its

movement so that sufficient force is always available to positively fire the cap. 55

Other and further objects pertaining to the construction and operation of the novel repeating cap pistol will appear hereinafter as the description proceeds and will be further pointed out in the attached 60 claims.

In the accompanying drawings and the following specification, there is disclosed by way of example, only, a single modification of the invention, it being understood, however, that various changes in the arrangement, size, shape and proportions of the various parts may be made by those skilled in the art without departing from the spirit of the invention, as particularly pointed out 70 in the attached claims. 65

In said drawings:

Figure 1 is a side elevation of the assembled pistol showing in dotted lines the position of the swinging side plate when opened 75 to allow the pistol to be loaded with a cap tape;

Figure 2 is a side elevation, the swinging plate and demountable portion of the handle having been removed to expose the operating mechanism, and further showing the magazine-hammer in the position it assumes just after firing a cap and ready to be operated again; 80

Figure 3 is a rear elevation of the pistol; 85

Figure 4 is a transverse vertical section on line 4—4 of Figure 2;

Figure 5 is a transverse vertical section on line 5—5 of Figure 2 looking in the direction of the arrows. 90

Figure 6 is a view similar to Figure 2 but showing the magazine hammer partially retracted under the action of the revolving triggers and the stop spring which cooperates with the caps contacting with the under side of the tape, its tip being adjacent the edge of a cap; 95

Figure 7 is a similar view showing the magazine-hammer in its fully retracted position just before being released by the trigger to strike the cap, and further showing the cap stop spring in the position it takes after release by one of the triggers; 100

Figure 8 is a transverse vertical section on line 8—8 of Figure 6 showing the manner in which the main casing and the swing-

ing plate combine to form a guide for the front, magazine-hammer, slide rod;

Figure 9 is a perspective view of the magazine-hammer with the twin spring removed;

Figure 10 is an elevation of the right side thereof;

Figure 11 is a perspective view of the cap stop spring;

Figure 12 is a horizontal section on line 12—12 of Figure 2 showing the manner of retaining the cap stop spring upon its supporting stud;

Figure 13 is a perspective view of the twin spring;

Figure 14 is a plan view of the spring washer used in conjunction with the revolving triggers;

Figure 15 is a transverse horizontal section on line 15—15 of Figure 1 showing the latching means for the swinging plate; and

Figure 16 is a side elevation of an operating crank which may be used in conjunction with the revolving triggers for firing the pistol rapidly.

In the manufacture of toy cap pistols of any type, and more particularly those having revolving triggers, great difficulty is experienced in producing them, in large quantities, at a reasonable price, since they must be made quite accurate in order to properly fire the caps which are often very irregularly spaced and vary in size. It is necessary to properly and accurately place each succeeding cap in a position between the firing hammer and anvil so that it will be exploded. Caps vary greatly in dimensions especially in diameter, and thus the distances between opposing edges of successive caps are not uniform. When the tape carrying the caps is being advanced to place a cap at the explosive position, the usual construction of pistol will feed the caps to many different positions between the hammer and the anvil, and due to the cumulative irregularities being transferred to each successive cap as it is fed, it frequently happens after a time that no cap is placed between the hammer and the anvil; or two caps are positioned and exploded, which prevents of course a constant succession of explosions, one for each trigger pull. Various manufacturing attempts, in connection with revolving trigger type pistols in large production, have not been successful due to the great irregularity encountered in castings and other parts used in assembling the pistols. These difficulties have prevented high speed feed of the caps with even a fair degree of success, often tearing the tape, stripping the caps from the tape, causing premature explosions of caps not positioned for exploding, and the burning of the cap or caps and tape adjacent the one being exploded by the hammer. The

pistol of the present invention overcomes all of these difficulties and will place each succeeding cap accurately in position between the hammer and the anvil so that all of the caps are fired, and even the last one on the tape is properly positioned between the hammer and anvil, which, as far as is known, has never been satisfactorily and positively done, before.

The above results are accomplished in the present invention by combining into one unit a majority of the parts necessary for the functioning of the pistol. Thus the hammer, tape magazine, tape adjusting and gripping springs, hammer cam, and other essential parts are formed as one element which is mounted within the casing for reciprocation upon three slides, forming the only contact between this part, which will be called the magazine-hammer hereafter, and the casing. The remaining operating parts comprises the revolving triggers, the tape positioning or cap-stop spring and the hammer torsion spring, all of which are mounted within the main portion of the casing. In this manner the spacings of the various parts instrumental in feeding the tape are automatically effected in the manufacture of the magazine-hammer and need not be arranged during assembly, thus eliminating one of the greatest sources of trouble in previously constructed and known cap pistols.

Referring to the drawings, there is disclosed a main casing 20 having a general contour intended to simulate a regular firearm of the automatic pistol type and comprising the handle portion 21, the barrel portion 22, the receiver portion 23, the muzzle 24 and the trigger guard 25, all of which are formed of a single casting having the right hand side open, as clearly disclosed in Figures 2, 6 and 7. The open side of the casing is adapted to be closed by two parts, the swinging plate 26 which can be opened for the purpose of positioning a cap tape within the magazine, and the removable handle portion 27 which serves to retain the swinging plate in position and provide a bearing for it. This removable handle portion is attached to the main casing by means of a screw or rivet 28 passing transversely through the handle.

The main casing and the removable handle portion provide bearings for the shaft 29 of the revolving triggers, which shaft at its left hand end is smaller in diameter and shorter than at the right hand end in order to insure its proper positioning in the casing during assembly. The right hand end of the trigger axle 29 provides a journal about which a sleeve 30 formed integral with the swinging plate 26 is adapted to rotate, so that the plate may be swung down to the position shown in dotted lines

in Figure 1 for the purpose of opening the tape magazine. An offset portion 31 on the removable handle portion 27 is provided with the aperture 32 which fits over this sleeve 30 and retains the swinging plate in position. The revolving triggers are thus mounted for free rotation between the two sides of the pistol casing, and a spring washer 33 is interposed between the revolving triggers and the left hand wall of the casing and surrounds the shaft 29 for a purpose to be later described. The trigger guard 25 is substantially concentric with the revolving triggers, and a part of the wall of the casing and the removable handle part are cut away to allow the individual triggers to pass within to operate the various parts of the pistol as later described.

A most essential part of the invention is disclosed best in Figures 9 and 10 and comprises the magazine-hammer, generally indicated by reference character 34. It is of irregular shape and comprises essentially the flat top wall 35, the left side wall 36, the magazine chamber 37, the cam face 38, the hammer striking face 39, the front slide rod 40 and the rear slide rods 41.

This magazine-hammer 34 is mounted for free reciprocation within the main casing, and for this purpose there are provided in the casing the rear slide rod guides 42 and the front slide rod guide 43 adapted to position and guide the previously described slide rods, so that the magazine hammer is free to reciprocate within the casing without any of its parts engaging the walls thereof. The rear slide rod guides comprise notches 42 in the rear wall of the receiver portion 23, cooperating studs 44 being provided on the removable portion of the handle to guide the right hand sides of the slide rods and retain them accurately within the notches 42. The rear view of the pistol shown in Figure 3 discloses that the handle is divided down the center up to the point 45 where it is offset and the removable portion carries only the thin cover plate 46 having the trim 47 corresponding to the trim 48 on the main portion of the casing. This trim 47 overlaps the rear wall of the casing to make a neat closure. The studs 44 are fastened to this trim 47 and smaller studs project from the trim 48 to give a symmetrical appearance to the rear of the pistol. The guide walls of the notches 42 and the edges of the studs 44 are rounded to provide the least possible amount of material for the slide rods to rub against, thus reducing the friction since these parts are castings and hence are liable to have a slightly roughened surface.

The main portion of the casing at its forward end is designed to simulate the muzzle of a pistol as shown at 24 and is thus hollow to the partition 49 in which is

provided a recess having parallel upper and lower walls and a semi-circular bottom and of a depth equivalent to the diameter of the front slide rod 40. Referring to Figure 8, this slot is disclosed at 43, and it will be noticed that the parting line between the swinging plate 26 and the muzzle portion of the main casing is at 50 so that the plate may be swung to one side without interference from the front slide rod. However, it may be desirable to provide means whereby the swinging plate is retained in closed position by means of the rod 40, and for this purpose it may be provided with an inward projection having therein a semi-circular slot in line with the rod 40 and considerably forward of the partition 43 so that the swinging plate may be placed in closed position only when the magazine-hammer is partially retracted, as shown in Figure 7, and is locked in position at all times when the rod 40 is in its extreme forward position and fits in this semi-circular slot. To further insure that the swinging plate will remain in a closed position no matter what the position of the slide rod 40, a depression 51 is provided near the top of the trigger guard into which the projection 52 formed integral with the swinging plate may fit, thus forming in effect a catch to retain the swinging plate closed. This construction is best disclosed in Figure 15.

From the above description it will be seen that the magazine-hammer portion is mounted in the casing and supported by the three slide rods so that it is free to reciprocate longitudinally but cannot move in any other direction. It is pressed forward normally under the action of the hammer torsion spring 53 which has the loop portion 54 arranged around a stud 55 cast integral with the handle part of the main casing; the lower end of the spring abutting against a stud 56 formed on the casing and the upper end resting against the hammer spring bearing 57 cast integral with the cam portion 38 of the magazine-hammer. Forward movement of the magazine-hammer is limited by the engagement of the hammer striking face 39 with the anvil 58 which is cast integral with and projects from the left wall of the main casing near the muzzle thereof and between which and the striking face, the caps are detonated. The magazine-hammer is retracted under the action of the revolving triggers, one of which cooperates with the cam face 38 while the one just forward of it is being pressed by the finger. Each of the triggers 59 is provided with a substantially semi-spherical end portion 60 sharply cut off at its extreme end as at 61 to provide a sudden and snappy release from the upper tip 62 of the cam face. The angle of the cam face is such that, as the trigger (closed in engagement with it in Figure 6) is

rotated, the magazine-hammer is retracted to the full extent of its movement by the time the trigger has reached the position shown in Figure 7 and is about to leave the 5 cam face to allow the hammer to be projected forward under the action of the torsion spring 53. The semi-spherical ends 60 are provided on the triggers in order that but a small surface may be presented to the 10 cam face to reduce the friction and thus ease the trigger pull, owing to the cast construction of these parts as previously described.

Referring more particularly to Figures 9 15 and 10 wherein are disclosed two views of the magazine-hammer, it will be noted that this is an irregular shaped, one-piece casting including as before described the top wall 35 supporting at its forward end the 20 front slide rod 40 and having depending from its left hand edge the side wall 36. The hammer proper having the striking face 39 extends outwardly from the side wall and beneath the top wall and is provided on its upper surface, which is downwardly and forwardly inclined, with the transversely arranged tape-gripping teeth 63. The side wall also carries projecting therefrom and parallel to the top wall the 25 transversely arranged tape adjusting teeth 64. At the rear, the top wall turns downward and forms the wall of the magazine chamber 37, the bottom of which is closed by a portion of the side wall of the magazine-hammer. Supported from the bottom 30 at right angles thereto is the tape roll stud 65 upon which the roll of cap bearing tape is adapted to be placed. As disclosed in the drawings, this cap tape stud is materially offset from the center of the magazine chamber. This is a very important feature 35 of the invention and serves to prevent at all times any jamming or clogging of the opening 66 between the wall of the magazine chamber cap guide 99 and the top wall 35 due to the momentum of the tape when the hammer carries it forward on the firing stroke. The rear wall of the magazine chamber has formed integral therewith the 40 rear slide rods 41 while the lower corner thereof supports the cam structure which includes the hammer spring bearing, as clearly shown in Figure 10. The side wall 36 is cut away as shown at 67 to allow the stud 89 to project therethru. The top and side walls have plane outer surfaces and the side wall is of substantially even thickness throughout, but, as disclosed best in Figure 10, the upper wall is materially 45 thinned out above the magazine chamber and then extends at an even thickness to the forward end thereof with the exception of the slight depression 68 adapted to accommodate the upwardly curved end of the 50 twin spring, and which may be thus called

the tape adjusting spring recess. The cap tape passes between the under surface of the upper wall of the magazine hammer and the two sets of teeth 63 and 64 and is retained in position on these teeth by spring pressure. For this purpose a leaf spring is arranged to press down upon the upper surface of the tape adjusting teeth 64 with a constant and unvarying pressure, and another flat spring is adapted to press down upon the surface of the tape gripping teeth 63 intermittently during the operation of the pistol. 70

It has been found preferable for simplicity and ease of construction to combine 80 these two springs into one, which will hereafter be called the twin spring. This twin spring 69 is best illustrated in the perspective view shown in Figure 13. It will be seen that it comprises a flat leaf spring 85 having the transversely offset and narrowed portion 70, the forward end 71, which is bent arcuately downward as at 72, and the rear end which first bends down as shown at 73 and then up at 74. This spring is 90 adapted to be mounted against the under surface of the top wall of the magazine hammer which is cut away at two places on either side of the stud 75 to receive it. The top of the stud 75 is recessed as shown 95 at 76 for a depth equivalent to the thickness of the spring 69 and for a width equivalent to the width of the narrowed portion of the spring with the shoulder 77 spaced inwardly 100 from the side wall 36 of the magazine hammer to prevent any accidental contact or friction between the ends of the twin spring and the inner surface of this side wall. The points 78 and 79 formed as a result of cutting the diagonal slots 80 and 81 to provide the stud 75 form fulcrums for the two parts of the twin spring so that the spring 105 is securely clamped between these fulcrums and the bottom of the recess 76 and each end thereof acts entirely independently of the other. The shoulder 82 on the end of the stud serves to maintain the twin spring in position on the stud at all times. The tape adjusting spring recess 68 serves to 110 accommodate the end 74 of the spring when it is raised by a cap passing between it and the teeth 64. 115

The remaining element in the construction is what may be termed the cap stop or positioning spring and is shown in detail in Figure 11. It comprises a leaf spring 120 83 having the substantially flat and straight end 84, the offset 85, the arcuate portion 86, the vertical end portion 87 and the loop or eye 88 which is adapted to fit over the stud 89 projecting outwardly from the left side wall of the main casing through the opening 67 in the side wall of the magazine hammer. In order that the spring may 125 be retained securely on this stud and diffi- 130

cultly removed, the stud is provided with 64 and the end 73 of the twin spring, then the shoulder 90 against which the saw teeth 91 at the end of the loop 88 abut. This construction is best disclosed in Figure 12 5 where it will be seen that the teeth are cut in such a direction as to be readily slipped over the stud but to hinder removal of the spring. Shoulders 89 at the bottom of the stud 89 retain the spring spaced from the 10 wall of the casing to prevent friction. The spring is so shaped and located that the arcuate portion 86 is within the radius of the triggers 59, one of which is adapted to come in contact with and elevate the cap 15 positioning spring upon rotation of the triggers, the first contact taking place at the point 92, as shown in Figure 6, just shortly before the succeeding trigger comes in contact with the cam face 38 to begin to 20 retract the hammer, and the offset portion 85 forms a release allowing the spring to drop after the trigger has passed beyond the point 93. The stud 94 projects outwardly from the left side wall of the main 25 casing to a position just beneath the point 93 and serves to limit the downward movement of this spring due to its resiliency.

The standard cap tapes are constructed with the caps arranged approximately $\frac{7}{16}$ of an inch center to center, but since the diameters are irregular no exact distance can be assigned to the spaces between the corresponding edges of adjacent caps. The pistol is constructed so that the total distance to which the hammer is retracted is $\frac{1}{2}$ inch. The reason for these differences in distance will appear in the description of the operation of the pistol.

The pistol constructed according to this invention is well adapted for rapid firing, and for this reason may be provided with a crank 95 adapted to cooperate with the revolving triggers to rotate them. For this purpose, the right hand end of the trigger shaft 29 is provided with a non-circular aperture 96 in which may be fitted the stub shaft 97 of the crank 95 to turn the triggers. The handle of the pistol is made considerably longer than usual so that the hand of the operator can grip it near its lower end, and the crank is offset, as shown in Figure 16, so that it will clear the fingers gripping the handle and thus be free for rotation.

55 *Operation.*

In order to load the pistol the swinging plate 26 is revolved to the position indicated in dotted lines in Figure 1, the projection 98 being provided for the purpose of affording a hold for the finger or thumb. A roll of cap carrying tape is placed in the magazine and over the stud 65 and the end 60 of the tape unrolled, passed over the tape guide 99, between the tape adjusting teeth 65

64 and the end 73 of the twin spring, then beneath the forward curved end 72 thereof and the tape gripping teeth 63. It will be noted that the tape is thus secured to the magazine-hammer in three places, i. e., the 70 tape roll stud, the tape adjusting teeth and the tape gripping teeth. Having reference now to Figure 2, the tape is shown positioned as just described and before the trigger is pulled. At each operation for the firing of a cap, three triggers are made use of, one being pressed by the finger, the one just forward of it actuating the cam to retract the hammer, and the next one forward raising and subsequently releasing the cap tape 75 stop spring. Upon pressure of the finger on the trigger extending into the trigger guard, the triggers are first rotated from the position shown in Figure 2 to the position shown in Figure 6, during which operation one of the triggers is brought into contact with the arcuate portion of the cap stop spring and raises it until the forward edge 100 thereof is brought first into contact with the under side of the tape and then presses the tape against the under side of the forward end of the twin spring and raises it out of engagement with the tape gripping teeth 63 and presses it against the under side of the top wall 35 of the magazine-hammer, 85 thus freeing the forward end of the tape from the hammer. The third trigger has meanwhile come into contact with the cam face 38 and the cooperation of these two parts then begins to retract the magazine-hammer. The tape is always gripped between the tape adjusting teeth 64 and the portion 73 of the twin spring so that the tape moves rearwardly with the magazine-hammer until the forward edge of the cap 105 stop spring meets the rearward edge of a cap preventing further rearward movement of the tape. Continued retraction of the magazine-hammer unwinds tape from the magazine as the tape is held stationary in 110 respect to the pistol casing by the cap stop spring, tension being maintained on the tape by means of the rear end of the twin spring and the tape adjusting teeth. This feeds the tape over the striking face of the hammer under the combined action of the downwardly curved end 72 of the twin spring and the natural resilience of the tape caused by the adhesive used in its construction and to its being rolled up for a long period. The 115 distance between the forward edge of the cap positioning spring and the detonating portion of the striking face of the hammer when in its full retracted position is equivalent to the distance between two caps plus 120 one half of the normal width of a cap so that by the time the hammer has reached its rearmost position a cap must be arranged over its striking face. Before the cam face 38 is released by the edge 61, of the trigger 125

130

cooperating with it, the preceding trigger moves past the point 93 of the cap stop spring, releasing it, and allowing it to fall against its stop 94 so that the following conditions prevail: Withdrawal of the tape positioning spring allows the return of the forward part of the twin spring so that the tape is thus gripped between the tape gripping teeth 63 and this spring; the tape is gripped between the tape adjusting teeth 64 and the rear portion of the twin spring; and the tape roll is supported upon its stud. Aside from these points of contact, the tape is entirely free for movement within the casting, which movement can only take place simultaneously with movement of the magazine-hammer, since the tape is carried by the magazine-hammer. The magazine-hammer is entirely free to move forward upon release by the trigger under the action of the torsion spring 53 which has been tensioned during the rearward movement of the magazine-hammer. These conditions are very favorable to a certain explosion of the cap since the magazine-hammer is free to move forward out of contact with all parts which might obstruct or slow up its movement and the tape with a cap positioned on the hammer face is fastened to the magazine-hammer and touches that alone. Further rotation of the trigger wheel results in the sudden release of the magazine-hammer by the sharp edge 61 of the trigger and its movement forward under the action of the hammer torsion spring, striking a cap against the anvil and firing it. It will be noted that it is unique in cap pistols to carry the cap on the hammer face and bring it into contact with the anvil rather than position the cap upon the anvil and strike it with the hammer.

It has previously been mentioned that the distance from center to center of the caps is $\frac{7}{16}$ of an inch, whereas the total distance through which the hammer is retracted is $\frac{1}{2}$ inch. The reason for this is to insure the forward edge of the tape positioning spring always being positioned behind a cap. Since these caps vary so much in diameter, it is necessary to insure that the cap is a sufficient distance forward of this edge before the spring is raised. By moving the magazine-hammer rearward $\frac{1}{2}$ inch from the position shown in Figure 2, it will be seen that the cap A will be drawn back into contact with the cap obstructing edge. In spite of careless loading, this cap cannot be positioned so that it will not be brought into contact with the edge during the rearward motion of the magazine-hammer. When the trigger releases the magazine-hammer the cap A will move forwardly $\frac{1}{2}$ inch in respect to the forward edge of the cap stop spring. Then assuming caps A and B to be of the same diameter the rear-

ward edge of cap B will be positioned $\frac{1}{16}$ of an inch forward of this edge which is a sufficient factor of safety to insure the edge being brought up behind the cap and not on top of it in which case the cap might slip under the spring when the hammer is again retracted. When the cap stop edge of the spring is then brought in contact with the tape the first rearward movement of the hammer results in the tape sliding under the forward edge of the cap stop spring until such edge contacts with the cap when movement of the tape is stopped. The cap indicated as C in Figure 2 is just forward of the tape adjusting teeth, and as the hammer is brought back the cap D must pass between these teeth and the rear portion of the twin spring, the tape adjusting spring recess 58 providing clearance to allow the spring to raise sufficiently to pass a cap.

The tape gripping teeth and spring have two functions. They first serve to maintain the tape securely in position on the hammer face during the firing stroke, and second they effectively prevent the cap succeeding the one being fired from being prematurely fire or burned and also prevent burning of the tape in the rear of the cap being fired. Reference to Figure 8 discloses that the cap succeeding the one being fired is arranged between these teeth and the spring and is thus protected.

The main casing of the pistol and the swinging plate are each provided with an enlargement 101 forming on the inside a gas pocket. This gas pocket is connected by means of a passage 102 between the front end of the pistol and the anvil with the outside atmosphere, thus permitting sudden expansion of the gases and their escape, preventing them from harming the tape within the pistol. The walls of these projections 101 are perforated as shown at 103 to further assist in the escape of gases. For the same purpose the bottom of the anvil and the striking face of the hammer are exposed beneath the barrel to the atmosphere. Both portions of the handle are provided with the apertures 104 cooperating to form a single opening through which small particles of burned paper and other dirt may pass out from the pistol. This opening also serves to relieve any back pressure within the pistol.

The slide rods project outwardly in the rear of the pistol for slightly over $\frac{1}{2}$ inch during the firing stroke, each time the trigger is pulled and afford, for the small boy, an additional amusement which has considerable merchandising value aside from enabling the simpler construction of the pistol and enhancing the speed of assembly as previously described.

From the above description it will be evi-

dent that there is provided by this invention a novel and improved repeating cap pistol which is simple in construction, neat in appearance, easy to manufacture, may be made by quantity production methods, is unfailing in operation, and which may be readily taken apart for cleaning and oiling. In order to prevent corrosion it is preferred to tin the springs. Actual experience with the pistol constructed according to this specification shows that even when it is worn considerably beyond the limits of tolerances allowed in manufacture, it still continues to accurately position a cap upon the striking face of the hammer with each pull of the trigger and unfailingly fires the cap thereafter.

Having thus described the invention, what is claimed as new and desired to be secured by U. S. Letters Patent is:

1. In a repeating cap pistol, in combination, a casing, an anvil therein, a hammer structure reciprocably mounted therein having a striking face for cooperation with said anvil, a tape roll support integral with said hammer structure and means between said support and striking face to secure the tape with a cap positioned on said face.

2. In a repeating cap pistol using cap tapes, in combination, a casing, an anvil therein, a hammer structure mounted for reciprocation therein, a striking face on said hammer structure for cooperation with said anvil, a cap tape magazine forming a part thereof, and a tape engaging spring carried thereby.

3. In a repeating cap pistol using cap tapes, in combination, a casing, an anvil therein, a hammer structure mounted for reciprocation therein, a striking face on said hammer structure for cooperation with said anvil, a cap tape magazine forming a part thereof, and a plurality of tape engaging springs carried thereby.

4. In a repeating cap pistol using cap tapes, in combination, a casing, an anvil therein, a hammer structure mounted for reciprocation therein, a striking face on said hammer structure for cooperation with said anvil, a cap magazine forming a part thereof, and tape engaging springs carried thereby, one of said springs exerting a constant pressure on said tape.

5. In a repeating cap pistol using cap tapes, in combination, a casing, an anvil therein, a hammer structure mounted for reciprocation therein, a striking face on said hammer structure for cooperation with said anvil, a cap magazine forming a part thereof, and engaging springs carried thereby, one of said springs exerting an intermittent pressure on said hammer structure.

6. In a repeating cap pistol, in combination, a casing, a unitary magazine-hammer construction, slide rods thereon, and guides

therefor in said casing whereby said magazine-hammer may be reciprocated in said casing.

7. In a repeating cap pistol, in combination, a casing, an anvil thereon, a unitary magazine-hammer reciprocably mounted thereon, a striking face thereon adapted to cooperate with said anvil, and slide rods on said magazine-hammer guided in said casing and projecting through a wall thereof.

8. In a repeating cap pistol, in combination, a casing, a magazine-hammer construction mounted for reciprocation therein, cap carrying means on said magazine hammer, slide rods extending beyond and forming a part of said magazine-hammer and guides in said casing to receive said rods.

9. In a repeating cap pistol, in combination, a casing, an anvil, a magazine-hammer mounted for reciprocation therein and having a striking face, means to withdraw said striking face from said anvil, cap tape carrying and adjusting means on said magazine-hammer and tape stop means adapted to maintain said tape stationary during withdrawal of said striking face.

10. In a repeating cap pistol including in combination a casing, an anvil, a magazine-hammer mounted for movement therein, and having a striking face, rotatable triggers adapted to withdraw said striking face from said anvil, cap tape carrying and adjusting means on said magazine-hammer and tape stop means, actuated by one of said triggers, and adapted to maintain said tape stationary during withdrawal of said striking face.

11. In a repeating cap pistol, in combination, a casing, rotatable triggers journaled therein, a magazine-hammer construction mounted for reciprocation by said triggers in said casing, means on said magazine-hammer to carry a tape roll, means on said magazine-hammer restraining the tape to move therewith, and means operated by said triggers to retain said tape stationary during a part of the movement of said magazine-hammer in one direction.

12. In a repeating cap pistol, in combination, a casing, rotatable triggers journaled therein, a magazine-hammer construction mounted for reciprocation by said triggers in said casing, a cap striking face thereon, an anvil adapted to cooperate therewith, means on said magazine-hammer to carry a tape roll, means on said magazine-hammer restraining the tape to move therewith, and means operated by said triggers to retain a part of said tape stationary with the caps thereof in a predetermined position during retraction of said magazine-hammer to position a cap on the striking face of said hammer.

13. In a repeating cap pistol, in combination, a casing, a magazine-hammer construc-

- tion mounted for reciprocation therein, means biasing said hammer in one direction, trigger means for retracting said hammer, a tape roll carrying stud on said magazine-hammer, a cap striking face remote from said stud, and means secured to said casing adapted to feed said caps to said striking face successively for each retraction of said magazine-hammer.
14. In a repeating cap pistol, in combination, a casing, an anvil therein, a magazine-hammer construction mounted for reciprocation therein and biased against said anvil, a striking face on said hammer adapted to cooperate with said anvil, a cap tape roll supporting means on said magazine-hammer remote from said striking face, means to grip said tape adjacent said striking face, trigger means to retract said magazine-hammer, and means, operative during the retraction, to release said tape gripping means.
15. In a repeating cap pistol, in combination, a casing, an anvil therein, a magazine-hammer construction mounted for reciprocation therein and biased against said anvil, a striking face on said hammer adapted to cooperate with said anvil, a cap tape roll supporting means on said magazine-hammer remote from said striking face, means to grip said tape adjacent said striking face, trigger means to retract said magazine-hammer, and means, operative before the retraction, to release said tape gripping means and obstruct the full retraction of said tape by said magazine-hammer.
16. In a repeating cap pistol, in combination, a casing, an anvil therein, a magazine-hammer construction mounted for reciprocation therein and spring-pressed against said anvil, a striking face on said hammer adapted to cooperate with said anvil to fire caps, a cap tape roll supporting stud on said magazine-hammer remote from said striking face, a tape gripping tooth adjacent said striking face, a spring cooperating therewith to hold the tape thereon, trigger means adapted to retract said magazine-hammer, a cap positioning spring having an edge below said tape, means on said trigger to elevate said cap positioning spring to release said first spring and hold a part of said tape thereagainst and stationary in respect to said casing during a part of the retraction of said magazine-hammer.
17. In a repeating cap pistol, in combination, a casing, an anvil therein, a magazine-hammer construction mounted for reciprocation therein and spring-pressed against said anvil, a striking face on said hammer adapted to cooperate with said anvil to fire caps, a tape roll supporting stud on said magazine-hammer remote from said striking face, tape gripping teeth adjacent said striking face, a tape gripping spring cooperating therewith to hold the tape thereon, trigger means adapted to retract said magazine-hammer, a tape positioning spring having a cap stopping edge below said tape, means on said trigger to move said tape positioning spring to release said first spring before moving the magazine-hammer, and to hold said tape thereagainst and stationary in respect to said casing during retraction of said magazine-hammer and means whereby said trigger means releases first said tape positioning spring and then said magazine-hammer.
18. In a repeating cap pistol, in combination, a casing, an anvil therein, a magazine-hammer construction mounted for reciprocation therein and having a cap striking face, said magazine-hammer spring-pressed to cause engagement of said striking face and anvil, a tape roll supporting stud on said magazine-hammer remote from said striking face, tape-gripping teeth near said striking face, tape-adjusting teeth between said tape-gripping teeth and tape roll supporting stud, a spring above each set of teeth pressing the tape thereon, trigger means to retract said magazine-hammer, a tape positioning spring mounted on said casing below said tape-gripping spring, means on said trigger means to elevate said tape-gripping spring, before reTRACTING said hammer, to contact with the lower surface of said tape to lift it and the tape-gripping spring from said tape-gripping teeth, a cap stopping edge on said tape-positioning spring adapted to prevent retraction of said tape by said magazine-hammer after engagement of a cap therewith and means whereby said tape positioning spring is released before the firing stroke of said hammer.
19. In a repeating cap pistol, in combination, a casing, an anvil therein, a magazine-hammer construction mounted for reciprocation therein and having a cap striking face, said magazine-hammer spring-pressed to cause engagement of said striking face and anvil, a tape roll supporting stud on said magazine-hammer remote from said striking face, tape-gripping teeth near said striking face, tape-adjusting teeth between said tape-gripping teeth and tape roll supporting stud, a one piece spring having an end above each set of teeth pressing the tape thereon, trigger means to retract said magazine-hammer, a tape positioning spring mounted on said casing below said tape-gripping spring, means on said trigger means to elevate said tape-gripping spring, before reTRACTING said hammer, to contact with the lower surface of said tape to lift it and the tape-gripping spring from said tape-gripping teeth, a cap stopping edge on said tape positioning spring adapted to prevent retraction of said tape by said magazine-hammer after engagement of a cap therewith to position

a cap on said striking face, and means whereby said tape-positioning spring is released before the firing stroke of said hammer.

20. In a repeating cap pistol including in combination, a casing, an anvil therein, a magazine-hammer construction mounted for reciprocation therein and having a cap striking face, said magazine-hammer spring-pressed to cause engagement of said striking face and anvil, a tape roll supporting stud on said magazine-hammer remote from said striking face, tape-gripping teeth near said striking face, tape-adjusting teeth between said tape-gripping teeth and said tape roll supporting stud, a spring above each set of teeth pressing the tape thereon, trigger means to retract said magazine-hammer, a tape positioning spring mounted on said casing below said tape-gripping spring, means on said trigger means to elevate said tape-gripping spring, before retracting said hammer, to contact with the lower surface of said tape to lift it and the tape-gripping spring from said tape-gripping teeth, a cap stopping edge on said tape positioning spring adapted to prevent retraction of said tape by said magazine-hammer after engagement of a cap therewith, and a stop to limit the return of said cap obstructing

30 spring.

21. In a repeating cap pistol, in combination, an anvil, a movably mounted magazine-hammer, means mounting said parts, a cap striking face on said hammer, a tape roll support thereon, trigger means to operate said magazine-hammer, and means for feeding said tape to said striking face during said operation of said magazine-hammer whereby a portion of the tape is stationary

40 and the forward end moves.

22. In a repeating cap pistol, in combination, an anvil, a movably mounted magazine hammer, means mounting said parts, a cap striking face on said hammer, a tape roll support thereon, trigger means to operate said magazine-hammer, and means for feeding said tape to said striking face during said operation of said magazine-hammer whereby a portion of the tape is stationary

50 and the forward end moves over the hammer face.

23. In a repeating cap pistol, in combination, an anvil, a movably mounted magazine-hammer, means mounting said parts, a cap striking face on said hammer, a tape roll support thereon, trigger means to operate said magazine-hammer, and means for feeding said tape to said striking face during said operation of said magazine-hammer

60 whereby a portion of the tape is stationary and its ends move.

24. In a repeating cap pistol, in combination, an anvil, a movably mounted magazine-hammer, means mounting said parts,

a cap striking face on said hammer, a tape roll support thereon, trigger means to operate said magazine-hammer, and means for feeding said tape to said striking face during said operation of said magazine-hammer whereby a portion of the tape is stationary, the forward end moves over the hammer face and the roll unwinds from its support.

25. In a repeating cap pistol, in combination, an anvil, a movably mounted magazine-hammer, means mounting said parts, a cap striking face on said hammer, a tape roll support thereon, trigger means to operate said magazine-hammer, and means for feeding said tape to said striking face during said operation of said magazine-hammer whereby a portion of the tape is stationary and the magazine-hammer moves beneath it allowing the end of the tape to move over the hammer face.

26. In a repeating cap pistol, in combination, an anvil, means for supporting a length of tape carrying a plurality of percussion elements and means for supporting said tape-supporting means and a striking means for cooperation with said anvil, means for moving said tape-supporting means and all the tape in one direction, during said movement of said supporting means, means for preventing the movement of a part of said tape during said movement of said tape in said one direction and means for simultaneously moving another part of said tape to position one of said percussion elements between said anvil and said striking means, means for interrupting the movement of said tape-supporting means and all of said tape in said one direction, and means for moving said tape supporting means and all the tape in a direction different to said first direction to cause explosion of said percussion element between said striking face and said anvil.

27. In a repeating cap pistol, in combination, a casing, a spring-pressed hammer element movably mounted therein, a rotatable shaft, substantially radial triggers thereon adapted to successively engage said hammer element to move it against the action of its spring, means thereon to release said hammer to permit its movement by said spring, and means to prevent engagement of the succeeding trigger with the hammer element during movement of the hammer under the action of its spring.

28. Rotatable trigger mechanism for use in a repeating toy pistol having a movable hammer including, a shaft, substantially radial triggers extending therefrom and semi-spherical ends on said triggers for operation of the hammer.

29. Rotatable trigger mechanism for use in repeating toy pistols, including a shaft, triggers radiating therefrom and having

- ends adapted for cooperation with operating parts of said pistol, and semi-spherical portions on said ends to reduce friction.
30. In a repeating cap pistol, a casing, an anvil, a device mounted for to and fro movement having a cap tape support and a striking face cooperating with said anvil to fire caps and a single spring having two ends operative to hold said tape on said device for feeding over said striking face.
31. A spring for use in repeating cap pistols including a central portion adapted to be rigidly supported, two fulcrum points and ends adapted to press on a cap tape.
32. A spring for use in repeating cap pistols including a central portion adapted to be rigidly mounted, two fulcrum points, an end adapted to bear on a cap tape and an end adapted to bend said tape into a firing position.
33. A repeating cap pistol including in combination an anvil, a casing, a magazine hammer therein, a tape compartment thereon, a cap tape roll support eccentrically mounted in said tape compartment and means to feed said tape cap by cap for firing on said anvil.
34. A device for supporting a cap tape roll in a repeating explosive mechanism including a cap tape guide means and a reciprocating tape roll supporting stud spaced from said guide means a distance greater than the maximum radius of said roll.
35. In a repeating cap pistol, in combination, an anvil, a casing, a striking mechanism adapted to cooperate with said anvil to fire caps, means to operate said striking mechanism, cap tape feeding mechanism and a cap tape roll supporting means movable in respect to said casing.
36. In a cap pistol having an anvil, a casing, means movable in respect to said casing for supporting a length of tape carrying spaced caps, means to advance said tape cap by cap to detonating position, including a reciprocating member the stroke of which is slightly greater than the spacing of the caps, whereby inequalities in the size or spacing of the caps or their improper positioning or insertion in the pistol does not affect the proper feeding.

In testimony whereof I hereunto affix my signature.

KOBY KOHN.
